UNITED STATES PATENT OFFICE.

ALBERT H. TAYLOR, OF WASHINGTON, DISTRICT OF COLUMBIA, ASSIGNOR TO WIRED RADIO, INC., OF NEW YORK, N. Y., A CORPORATION OF DELAWARE.

RADIO SIGNAL CIRCUITS.

Application filed January 7, 1925. Serial No. 1,054.

The particular object of my invention is to provide a radio frequency device to be used as a master oscillator or as a heterodyne wave meter whereby the frequency generated 5 locally remains constant over a wide variation of filament current or of plate voltage or variations in the characteristics of the tubes used.

A further object of my invention is to provide a device to be used in connection with the reception of radio frequency signals, especially signals of very short wave lengths, that require a particularly constant frequency in the local oscillating circuits that autodyn- 15 ing with the incoming waves may be successful.

With these and other objects in view my invention will be best understood by reference to the accompanying drawing in which Figure 1 represents my invention as applied to a constant frequency driver and Figures 2, 3, and 4 represent my invention as applied to radio receiving circuits.

1 represents a three electrode vacuum tube, 25 with grid leak 2 and grid condenser 3 connected as shown. When certain types of tubes, such as a 5-watt power tube is used, the grid condenser 3 may be short circuited with beneficial results. The filament is heat- 30 ed by a separate local battery as shown.

Referring more particularly to Figure 1, coil 4 in the plate circuit and coil 5 in the tuning circuit are fixed in value and position. Condenser 6, which performs the 35 function of exciting and controlling the grid may be kept at a fixed value, or it may be varied in such a manner as to keep its value always several times larger than the condenser 7. Tuning is accomplished by 40 condenser 7, and sometimes also by condenser 6 which condensers should be of a precision type. For extremely wide ranges of tuning it may be necessary to provide switches to vary the inductance in coils 5 and 4 but 45 during operation over normally wide ranges of frequency the inductances 5 and 4 are fixed and tuning is accomplished solely by varying the condensers 7 and 6. The mutual inductance between coils 5 and 4 will be 50 different for the different values of the inductances of each coil but as the coils remain immovable and the inductance of the coils are not changed during tuning, the mutual inductance will remain constant for 55 any definite range of frequencies. The grid

leak, which must be connected between the grid and the filament, should be of somewhat smaller value than is customary. The power for the plate circuit may be from any external direct current source, such as the 60 battery 8. Condenser 9 is in parallel with the battery to provide a low impedance path for the high frequency oscillations. A telephone may be inserted at 10 to give an indication, by a click, as to when the circuit 65 is oscillating or in case this invention is used in connection with a receiving circuit, an audiofrequency responsive apparatus is connected at this point. Hot wire am- 70 meters may be placed in the plate and grid circuits to indicate any unusual conditions, such as abnormal plate current or abnormal grid current due to the use of a defective tube.

It will be seen that the grid excitation 75 voltage, being obtained by using the drop of potential across the condenser 6, is practically independent of the frequency. If the frequency rises, the induced voltage across coils 5 and 4 increases but at the same time the drop across the excitation condenser 6 per unit of current in condenser 6 falls. If the grid is taking normal ex- 80 citation, this can remain constant only when the current in the main oscillating circuit is 85 itself constant. Furthermore, as the grid excitation voltage is particularly independent of the frequency, the frequency, also, is almost completely independent of the temperature of the filament, and of the volt- 90 age of the plate battery 8. Tubes may be interchanged in this circuit with but little effect on the frequency even when they are 95 of different types.

My invention, as applied to receiving cir- 95 cuits using the autodyne system of reception of continuous wave signals, is shown in Figures 2, 3, and 4. In Figure 2 the signal receiving circuit is coupled to the coil 12 in the secondary circuit by means of 100 coil 11. When the coupling between 11 and 12 is loose, the tuning of the signal receiving circuit has no effect on the frequency of the local oscillating circuit.

In Figure 3 the signal receiving circuit is 105 coupled to coil 12 in the plate circuit by coil 11. When the coupling between 11 and 12 is loose, the tuning of the signaling circuit has no effect on the frequency of the local oscil- 110 lating circuit.

In the circuits as set forth in Figures 2 and 3 control of regeneration is obtained by altering the coupling between coils 11 and 12. If this coupling is tightened up to the point where oscillations cease, the frequency will change but one or two kilo cycles at short waves, but this change is not enough to throw the signals out of tune. The detuning never amounts to more than 10 $\frac{1}{4}$ of one per cent. This permits non-oscillatory reception at the same calibrated settings as used for C. W. reception, by simply making the coupling tight enough to stop oscillation.

15 In Figure 4 the signal receiving circuit is coupled by means of coil 11 to coil 12 in series with the grid leak 2. This arrangement gives the most constant frequency and even when a tight coupling exists between 20 11 and 12 tuning in the receiving signal circuit has no effect whatever on the local frequency generator. However, this circuit can be used only for reception of continuous wave signals as there is no way of controlling the regeneration except by changes of 25 filament temperatures, which is considered unsatisfactory.

What I claim is:

1. A generator of high frequency electrical oscillations comprising in combination an electron tube having grid, filament and plate electrodes, input and output circuits interconnecting said electrodes, an inductance included in each of said circuits 30 and coupled one to the other, the inductance in said input circuit being connected in 35

series with a pair of condensers, one of said condensers being connected in shunt with said input circuit for controlling the excitation of said grid independent of variation in frequency. 40

2. A system for generating high frequency electrical oscillations comprising in combination an electron tube having grid, filament, and plate electrodes, input and output circuits interconnecting said electrodes, 45 a pair of mutually coupled inductances, one connected in said input circuit and the other connected in said output circuit, a pair of condensers arranged in series with the inductance in said input circuit, one of said condensers having a substantially larger 50 electrical capacity than the other, and a parallel connection between said last mentioned condenser and said input circuit. 55

3. A system for generating high frequency electrical oscillations comprising in combination an electron tube having grid, filament and plate electrodes, input and output circuits interconnecting said electrodes, 60 a pair of mutually coupled inductances, one connected in said input circuit and the other connected in said output circuit, a pair of condensers, one of said condensers being connected in series with said input circuit, and 65 the other of said condensers being connected in shunt with said input circuit, said last mentioned condenser having a value substantially larger than said first mentioned condenser.

ALBERT H. TAYLOR.
